UNITED STATES PATENT OFFICE.

WILLIAM REDETT, OF FREDERICKSBURG, OHIO.

SLATE ROOF.

SPECIFICATION forming part of Letters Patent No. 357,503, dated February 8, 1887.

Application filed April 23, 1886. Serial No. 199,929. (No model.)

To all whom it may concern:

Be it known that I, WILLIAM REDETT, a citizen of the United States, residing at Fredericksburg, in the county of Wayne and State 5 of Ohio, have invented certain new and useful Improvements in Slate Roofs, of which the following is a specification, reference being had therein to the accompanying drawings.

The object of my invention is to provide a 10 slate roof of such construction that the slates may be laid directly on the rafters, if desired, and the joints thereof be so tight that it will be practically impossible for any rain or snow to get through the roof.

15 In the accompanying drawings, Figure 1 is a plan view of a portion of a roof embodying my invention; and Fig. 2 is a section of the same on line 2 2, Fig. 1. Figs. 3 and 4 are detail views of one of my non-conducting slates.

20 A denotes the rafters of the building, and B the larger slates, (preferably about fourteen by twenty-four inches in size,) which may be nailed directly to the rafters, these slates being laid lengthwise of the roof, or with their 25 sides extending up the roof, as shown in the drawings. These slates have a lap of about two inches, and between the lapping edges I prefer to spread a narrow line of hydraulic or other water-proof cement. (Indicated by a.)

30 The joints b between the ends of the slates B are covered by narrow overlapping cap-slates C, which (excepting the lowest one) are of a length which is greater than the width of the large slates B, so that each of the said cap-slates will cover the nails c, by which the cap-slate below is secured in place. Between the 35 cap-slates C and the large slates B, I prefer to spread a line or coating of cement. (Indicated by d.)

40 The cement between the lapping edges of the slates B, and also between the slates B and the cap-slates C, is preferably applied in a semi-fluid condition by a reservoir-syringe, a line of cement being run along the edges of the 45 upper surfaces of the slates just before the overlapping slates are laid in place.

To render my improved roof more or less impervious to heat, I prefer to cover the slates on their under sides with a coating of some adhesive paint, on which is sprinkled, while the paint is still wet, sawdust or other similar fine non-conducting material, which will permanently adhere to the slate when the paint is dry.

Having thus described my invention, I claim 55 and desire to secure by Letters Patent—

1. In a slate roof, the combination, with the large overlapping slates arranged lengthwise of the roof, of the smaller overlapping cap-slates covering the joints between the ends of the large slates, and having a length which is greater than the width of the said large slates, substantially as set forth.

2. In a slate roof, the combination, with the large overlapping slates B, extending lengthwise of the roof, of the overlapping cap-slates C, covering the joints between the ends of the slates B, and having a length which is greater than the width of the said slates B, and a line or joint of cement between the cap-slates C 60 and the slates B, substantially as set forth.

3. In a slate roof, the combination, with the large overlapping slates B, extending lengthwise of the roof and having cement between their lapping edges, of the overlapping cap-slates C, covering the joints between the ends of the slates B, and having a length which is greater than the width of the said slates B; and a line or joint of cement between the said cap-slates C and the slates B, substantially as 75 set forth.

4. A slate roof composed of slates provided on their under sides with a non-conducting coating consisting of a comminuted material secured to the slates by an adhesive substance, 80 substantially as set forth.

In testimony whereof I affix my signature in presence of two witnesses.

WILLIAM REDETT.
